UNITED STATES PATENT OFFICE.

JOHN A. SECOR, OF LA PORTE, INDIANA, ASSIGNOR TO ADVANCE-RUMELY COMPANY,
A CORPORATION OF INDIANA.

EXHAUST NOZZLE AND ASSEMBLY.

Application filed April 12, 1922. Serial No. 552,019.

To all whom it may concern:

Be it known that I, JOHN A. SECOR, a citizen of the United States, residing at La Porte, in the county of La Porte and State of Indiana, have invented a certain new and useful Improvement in Exhaust Nozzles and Assemblies, of which the following is a specification.

This invention relates to the construction 10 of a radiator and the exhaust arrangement of an internal combustion tractor and particularly to the combination of the two whereby the exhaust is satisfactorily muffled and whereby the power from the exhaust is 15 utilized to draw air through the radiator. It has for one object the combination of a radiator with an exhaust to assist in the passage of air through the radiator. It has for another object to muffle the exhaust. Other 20 objects will appear from time to time throughout the specification and claims.

My invention is illustrated more or less diagrammatically in the accompanying drawings, wherein:

25 Figure 1 is a side elevation of the radiator assembly with parts broken away;

Figure 2 is a front elevation of the same;

Figure 3 is a plan view;

30 Figure 4 is a plan view of the exhaust nozzle on an enlarged scale with parts broken away;

Figure 5 is a vertical cross section of the same with parts broken away.

Like parts are designated by like characters throughout.

40 A is a radiator housing, open at its bottom, in which the radiator B, of which the front section is partially shown, is positioned. There is here shown a radiator which is built up of a plurality of vertical sections, spaces being left between each section. A radiator of almost any other type might, however, be used in this connection. The details of the radiator will not here be 45 described as they form no part of the present invention. The radiator sections are tied together by bolts of which only the heads C C are here shown. The discharge connection for the fluid is here shown as at C' the supply connection being omitted.

50 The top of the radiator housing is closed by a hood D which terminates in the flared funnel D'. This funnel is circular in cross section and flared outwardly as shown.

55 Within the hood D and above the radiator is

positioned the exhaust nozzle E. As shown the nozzle comprises an annular channel E' provided about its top with an annular opening E². Communicating with this annular channel is a tubular section of the nozzle which is provided with two branches E³ E³. In the form here shown the nozzle is adapted primarily for use with a two cylinder engine. Each of the cylinders is connected to one of the passages E³ E³. This arrangement obviously might be varied. There might be more than two passages E³ or there might be but one. At one side the nozzle is provided with the laterally extending ears E⁴ E⁴ by means of which it is supported upon and secured to the framework of the radiator casing. At its opposite side it is provided with the arm E⁵ which is also supported from and secured to the framework of the radiator casing. 75

Although I have shown an operative device, still it will be obvious that many changes in form, shape and arrangement of parts may be made without departing materially from the spirit of my invention, and I wish therefore that my showing be taken as in a sense diagrammatic. 80

As appears particularly in Figure 5 there is provided in the annulus a depression in line with the incoming gases. The depression is adapted to collect water which may be carried with the gases or condensed out from them. It is provided with a perforation so that water may be discharged and the annulus kept at all times substantially free from water. Between this depression and the exhaust connections, and thus between it and the onrushing gases, is a raised baffle. The purpose of this is to prevent direct blasts of gases from coming upon the water in the depression and blowing it downward about the annulus. 90

The use and operation of my invention are as follows:

When the elements of this combination 100 are assembled as shown in the drawings, they form part of and are associated with a tractor which is propelled by an internal combustion engine. The exhaust ports of the engine are connected to the exhaust nozzle so that burned gases from the cylinders are exhausted into the nozzle. The radiator shown is connected with the cooling jackets of the engine and the cooling fluid is circulated through the radiator. The casing 105 110

- which encloses the radiator is open at the bottom and at the top. When the engine is in operation, burned gases are exhausted into the tubular part of the exhaust nozzle and because of their force they tend to rush about the annular portion of the nozzle. As above noted the particular arrangement here shown is intended to be combined with a two cylinder engine, the cylinders operating alternately so that first one will exhaust and the gases will be discharged into the nozzle and will rush about the annular portion of it and then the other cylinder will discharge and its gases will rush about the opposite side of the annular portion and in the opposite direction. In this operation the force of each exhaust charge is practically expended before the gases have made a complete circuit of the annular portion of the exhaust nozzle. Since the annular portion of the nozzle is open about its upper side, the moment the gases strike it some of them escape upward, and it is this upward escape of the exhaust gases which to a considerable extent serve to diminish their velocity. The velocity of the exhaust gases is thus largely diminished and the noise of the exhaust is muffed.
- The arrangement shown, however, has an additional purpose. Since the exhaust gases are discharged upward from out the annular portion of the nozzle and since the radiator casing is open both at its top and its bottom the exhaust gases set up a current of air, drawing air in at the bottom of the casing and discharging it at the top by an injector action. During the time of the operation of the engine there is, therefore, a continual current of air passing through the radiator casing. The air which is about the radiator, of course normally becomes heated and this air of itself will rise and will pass out of the radiator casing and will therefore set up something of a current of air, but the arrangement of the exhaust nozzle and the exhaust gases greatly increases the flow of air, and thus very greatly multiplies the quantity of air which will pass through the radiator in a given time and so serves to improve its cooling qualities. 50
- The hood over the top of the radiator casing serves to constrict to some extent the passage through which the air must pass. It is to be noted that the upper edge of the passage where it joins the lower edge 55 of the funnel is larger in diameter than the annular opening in the top of the exhaust nozzle and that it is situated above the exhaust nozzle and that the upper edge of the funnel is flared outwardly from its lower edge. This combination greatly improves the action of the assembly and increases the amount of air which is drawn through the radiator and the radiator casing. This effect is in some measure due to the modified 60 venturi which is formed by the arrangement of the parts just described. 65
- I claim:
1. As a new article of manufacture an engine muffler, said muffler being generally 70 annular in shape and provided with an annular exhaust opening, an exhaust impulse balancing means comprising a plurality of oppositely directed separate exhaust connections communicating with said muffler 75 whereby exhaust discharges are directed in opposite directions to balance each other.
  2. In combination with an internal combustion engine a muffler shaped generally in the form of an annulus and provided with 80 an annular exhaust opening, and provided also with exhaust impulse balancing means comprising a plurality of oppositely directed exhaust connections communicating with the interior of said muffler whereby successive 85 exhaust discharges are directed in opposite directions about said annulus and balance each other.

Signed at La Porte, county of La Porte, and State of Indiana, this 6th day of April 1922.

JOHN A. SECOR.
